UNITED STATES PATENT OFFICE.

EDWARD R. WILLIAMS, OF SHARPSBURG, PENNSYLVANIA, ASSIGNOR OF ONE-THIRD TO JOSEPH WILLIAMS AND ONE-THIRD TO WILLIAM H. WILLIAMS, BOTH OF SHARPSBURG, PENNSYLVANIA.

DISINFECTING APPARATUS.

1,096,143.

Specification of Letters Patent. Patented May 12, 1914.

Application filed January 11, 1913. Serial No. 741,593.

To all whom it may concern:

Be it known that I, EDWARD R. WILLIAMS, a resident of Sharpsburg, in the county of Allegheny and State of Pennsylvania, have 5 invented a new and useful Improvement in Disinfecting Apparatus, of which the following is a specification.

This invention relates to disinfectors and deodorizers, and particularly to the supporting means therefor.

The object of the invention is to provide simple and inexpensive means for firmly and rigidly supporting the receptacle and the cup or cups from which the liquid disinfectant or deodorant is discharged, and which prevents wear of the cup by contact of the receptacle therewith, and is cleanly and sanitary.

Other objects of the invention are in part 20 obvious and in part will appear hereinafter.

In the drawings Figure 1 represents a sectional elevation through a disinfecting and deodorizing apparatus and a bracket for supporting the same, embodying the invention; Fig. 2 is a perspective view of the bracket or support shown in Fig. 1; Fig. 3 is a detail sectional elevation of the lower supporting arm of the bracket and a portion of the receptacle and cups, and illustrating a modification; Fig. 4 is a perspective view of the bracket illustrated in Fig. 3; Fig. 5 is a detail sectional view on the line 5—5, Fig. 1; Fig. 6 is a similar view on the line 6—6, Fig. 4; Fig. 7 is a detail perspective view of a cup shown in Fig. 3; and Fig. 8 is a detail view of a retainer.

The disinfecting or deodorizing apparatus shown in the drawings comprises a receptacle 1, which may be of any size or 40 shape, but preferably is in the form of a cylindrical glass bottle which is closed at its upper end, as at 2, and at its lower end is reduced to provide a central outlet 3. The first reduction in the diameter of the receptacle provides an annular wall 4 which is inset from the periphery of the receptacle and is threaded for a purpose which will 45 hereinlater appear. This reduction also forms an annular shoulder 5 extending from the threaded wall 4 to the extreme outer 50 wall of the receptacle. The second reduction 6 forms the outlet 3 and provides clearance for a wick 7 that is used in connection with the receptacle.

The disinfectant or deodorant 8, which is 55 contained within the receptacle 1, flows out through the bottom outlet 3 into an inner cup 9, which is threaded at its upper edge so that it can be screwed upon the threaded annular wall 4 of the receptacle. In operation, sufficient of the disinfectant or deodorant flows by gravity from the outlet 3 into the cup 9 to form a liquid seal for the receptacle, thereby preventing air from entering the receptacle and hence also preventing further flow of liquid therefrom until enough of the liquid is removed from the cup 9 to break the liquid seal, as will be readily understood. The side wall of the cup 9 is provided with one or more apertures 10, three being shown, which are preferably arranged at different levels. The wick 7 is made of suitable material and is arranged with one end lying in the liquid in the cup 9 and the other end extending 65 through any one of the apertures 10 in the cup 9 to the outside of the cup and down the side thereof, in order that the contents of the cup 9 may be conveyed therefrom by capillary action. The amount and rapidity 70 of flow may be regulated by placing the wick in the various holes or apertures 10, or by using one or more wicks. The wick is held in proper position close to the wall of cup 9 and with its inner end in the liquid 75 by a retainer 11, formed of thin sheet metal having its outer portion channeled, as at 12, to confine the wick, and its inner portion reduced, as at 13, and passing through one 80 of the apertures 10. The extreme inner end 85 of the retainer is provided with edge projections 14 to embrace the wick and retain it in position as stated. It will of course be understood that the reduced end of the retainer is small enough to pass through the 90 apertures 10 and that it is bent or folded on itself into the shape shown after being passed therethrough.

15 denotes an outer cup, which is of a depth and diameter greater than the inner 100 cup 9, and at its upper edge is provided with an annular flange or bead 16, preferably of less diameter than the largest diameter of the receptacle. The outer end of the wick 7 extends down through the channeled portion 12 of the retainer to the bottom of the cup 15 to convey the contents of the inner cup 9 to the cup 15, and the lat-

ter is provided at one side with a discharge tube or outlet 17, hereinafter to be referred to.

The receptacle 1 and the cups used there-
5 with are supported by a bracket, which in
the present instance comprises a base 18, in
the form of an elongated bar, preferably
formed of cast metal, and provided with
suitable means for securing it to a wall or
10 support, such as the screw-holes 19. Said
base at its lower end is provided with a rec-
tangular boss 20 which fits in a similarly
shaped socket 21 in one end of an arm 22,
the other end of which is in the form of a
15 ring or annulus 23 which surrounds the
outer cup 15 and supports the cup and re-
ceptacle. To rigidly secure the arm 22 to
the base 18, a screw 24 is passed from the
rear through an aperture in the base 18 and
20 boss 20 and is threaded into a socket in the
end of the arm 22. The rectangular boss 20
and the socket into which it fits provide a
very firm connection and prevent rotation
of the arm on the boss, thus holding the
25 ring or annulus 23 in a horizontal plane
with the receptacle and cups on a vertical
axis. Ring or annulus 23 may, however, be
integral or in one piece with the base 18, if
desired.

30 The flange or bead 16 on the cup 15 may
rest directly upon the upper edge 25 of the
ring 23 to support the cup, as indicated in
Fig. 1, in which case the annular flat shoul-
der 5 of the receptacle 1 rests upon the
35 flange or bead 16 of the cup 15, thereby sup-
porting the receptacle upon the cup. Prefer-
ably, however, the ring 23 is provided
with an annular groove or depression 26, to
receive and conceal the flange or bead 16 of
40 the cup, in which case the annular flat shoul-
der 5 of the receptacle rests directly upon the
upper edge 25 of the ring, as shown in Fig.
3. The cup and receptacle are thus sepa-
rately supported by the ring 23 so that there
45 is no contact between the receptacle and
the cup 15. This is desirable because the cup
15 is preferably formed of brass or like ma-
terial, provided with a non-corroding coat-
ing, such as by being nickel-plated, and if
50 the receptacle contacted with the cup this
coating would soon wear off. Moreover, the
close fit between the receptacle and ring pre-
vents dirt or water getting into the outer
cup and interfering with proper operation.

55 The upper end of the base 18 is provided
with a lateral boss or enlargement 27 which
is preferably channeled in its side faces, as
at 28, to receive the opposite ends 29 of a
holding arm or member 30, which prefer-
60 ably comprises a metal strap bent to form
an annulus or ring-like portion 31 which
surrounds the reduced upper end 2 of the
receptacle 1. The ends 29 of the arm 30 are
provided with apertures 32 and the boss 27
65 is provided with an aperture 33 through

which is passed a bolt 34 having a nut 35 to removably secure the arm 30 to the base.

To fill the receptacle the nut 35 is loosened
70 to enable the holding arm 30 to be swung
upwardly away from the receptacle 1, the
bolt 34 acting as a pivot. The receptacle 1
and the inner cup 9 are then lifted out of
the bracket, leaving the outer cup 15 sup-
75 ported by the lower arm thereof. The cup 9
is unscrewed from the receptacle and the
latter is then inverted and filled. The cup
9 is now replaced on the receptacle and the
latter again inverted to the position shown
80 in Fig. 1 and replaced in the bracket. Suf-
ficient of the liquid flows from the bottom
outlet into the inner cup, to form a liquid
seal, as stated. The receptacle and the cup
9 being placed in position in the bracket,
the upper arm is then swung down and the
85 nut 35 tightened to rigidly clamp the re-
ceptacle in position. The material in the
inner cup is conveyed to the outer cup by
the wick 7 and flows out through the dis-
charge tube 17.

Under some circumstances it is advisable
90 to have the discharge tube 17 located as close
to the base 18 as possible, as when the liquid
is to be conducted from the discharge tube,
by a suitable conduit, to a closet or the like,
while in other cases it is desirable to have
95 the discharge tube as far from the base as
possible, as when the liquid is intended to
drip from the discharge tube 17 into a urinal.
For this purpose I provide means for
retaining or locking the cup 15 in any one
100 of a plurality of positions. This means may
be of the character shown in Fig. 1 and com-
prising oppositely disposed sockets or
notches 36 in the inner face of the ring 23,
with which co-operates a boss or projection
105 37 formed by pressing out a small portion
of the material of the cup 15. Cup 15 may
be placed in the ring so that the projection
37 engages either of the notches 36. Prefer-
ably, however, the cup 15 is formed with a
110 portion of its wall or flange non-circular,
that is, either triangular, square, pentagonal,
hexagonal, or with any number of sides, but
preferably with an even number, as shown
at 38, Fig. 7, where the cup shown is hex-
agonal in shape. In this case the ring 23 is
115 formed with inner projecting portions 39,
making the inner wall of the ring hexagonal
in shape to fit the cup. Obviously, by re-
moving the cup from the ring and rotating
it through angles of 60°, 120°, or 180°, the
position of the discharge outlet 17 may be
varied as desired, to place the same nearer
120 to or farther from the base 18. I also pre-
fer to provide means for preventing rotation
of the receptacle 1 in the bracket in order
that advertising devices or other insignia,
which may be imprinted or placed upon the
receptacle, may be permanently held in po-
125 sition at the front of the apparatus. In
130

the form shown in Fig. 1 this comprises a small boss or teat 40 which projects from one side of the reduced upper end 2 of the receptacle and into the space between the 5 members 29 of the arm 30. The portion 31 of the arm 30 may, however, be polygonal in shape, as shown in Fig. 4, in which case the reduced portion at the upper end of the receptacle will be of corresponding shape 10 and thus prevent rotation of the receptacle therein. It will also be understood that, instead of providing sockets or channels 28 in the side walls of the boss 27 to receive the arms 29 of the upper member 30, I may 15 form the boss 27 with flat sides and provide the arms 29 with channeled ends 41 to surround or embrace the boss, as shown in Fig. 6.

The apparatus described is simple and effective and can be cheaply constructed. The supporting bracket is made of but few parts and rigidly holds the disinfecting apparatus in the proper position to deliver the disinfectant or deodorant to the place desired.

25 What I claim is:—

1. A disinfecting apparatus, comprising a receptacle having a bottom outlet, a cup surrounding the lower end of the receptacle and arranged to receive liquid therefrom 30 and provided with a projecting edge portion, and a bracket or support comprising a base adapted to be secured to a wall, an arm thereon provided with a ring-like portion surrounding said cup and having a groove to 35 receive the projecting edge portion of said cup and support the same, and said receptacle above said cup having a portion resting on the upper edge of said ring-like arm.

2. A disinfecting apparatus, comprising 40 a receptacle having a bottom outlet, a cup surrounding the lower end of said receptacle and arranged to receive liquid therefrom, a bracket or support therefor comprising a base adapted to be secured to a wall, and an 45 arm thereon provided with a portion surrounding said cup and having a non-circular inner wall, said cup being provided at one side with a discharge outlet for liquid and having a portion shaped to correspond 50 with the non-circular portion of said arm to thereby prevent rotation of the cup in said arm, said cup being adapted to be placed in different positions in said arm with said discharge outlet at different distances 55 from the base.

3. A disinfecting apparatus, comprising 60 a receptacle having a bottom outlet, a cup surrounding the lower end of the receptacle and arranged to receive liquid therefrom, said cup being non-circular in shape and provided with a projecting edge portion, and

a bracket or support comprising a base adapted to be secured to a wall, an arm thereon provided with a ring-like portion surrounding said cup and shaped to correspond therewith and having a groove to receive the projecting edge portion of said cup and support the same, said cup at one side being provided with a discharge outlet and being adjustable in said arm to place said outlet at different distances from said base. 65

4. A disinfecting apparatus, comprising a receptacle having a bottom outlet, a cup surrounding the lower end of the receptacle and arranged to receive liquid therefrom, 70 said cup being non-circular in shape and provided with a projecting edge portion, and a bracket or support comprising a base adapted to be secured to a wall, an arm thereon provided with a ring-like portion 75 surrounding said cup and shaped to correspond therewith and having a groove to receive the projecting edge portion of said cup and support the same, said receptacle above said cup having a portion resting on the upper edge of said ring-like arm, and said cup at one side having a discharge outlet for liquid. 80

5. A disinfecting apparatus, comprising a receptacle having a bottom outlet, a cup 90 surrounding the lower end of the receptacle and arranged to receive liquid therefrom and provided at one side with a discharge outlet, a bracket or support comprising a base adapted to be secured to a wall, an arm 95 thereon provided with a portion surrounding said cup, said cup and arm being so shaped that the cup may be held in different angular positions in said arm, an upper arm on said base having a portion surrounding 100 the upper end of said receptacle, and inter-engaging parts on said receptacle and upper arm arranged to lock the receptacle non-rotatably in a single position in said bracket.

6. A disinfecting apparatus, comprising 105 a receptacle having a bottom outlet, a cup surrounding the lower end of the receptacle and arranged to receive liquid therefrom and provided with a discharge outlet for liquid, a bracket or support comprising a 110 base adapted to be secured to a wall, a lower arm thereon arranged to support said cup, an upper arm on said base arranged to engage said receptacle, and means for preventing rotation of said receptacle in said upper 115 arm.

In testimony whereof, I have hereunto set my hand.

EDWARD R. WILLIAMS.
